UNITED STATES PATENT OFFICE.

THOMAS W. NEELY, OF MARSHALL, ILLINOIS.

ROTARY ENGINE.

SPECIFICATION forming part of Letters Patent No. 717,598, dated January 6, 1903.

Application filed April 18, 1901. Serial No. 56,492. (No model.)

To all whom it may concern:

Be it known that I, THOMAS W. NEELY, a citizen of the United States, residing at Marshall, in the county of Clark and State of Illinois, have made certain new and useful Improvements in Rotary Engines, of which the following is a specification.

My invention is an improvement in that class of rotary engines which are provided with abutments adapted to slide radially in the casing and with a cylindrical piston arranged concentrically in said casing and having a series of radial wings between which and the abutments the steam acts expansively to cause rotation of the piston.

The invention consists particularly in the construction and arrangement of the steam-induction valves and their operating mechanism, the governor and cut-off, and the relation of the piston-wings to the abutments for working steam expansively and securing uniform rotation of the piston.

In the accompanying drawings, Figure 1 is a side view of my improved engine. Fig. 2 is a central vertical section of the engine. Fig. 3 is a vertical section taken on a line between the casing and governor. Fig. 4 is a vertical section on a line exterior to the governor.

The cylindrical casing A is fixed horizontally upon a suitable bed or base B, and a cylindrical piston C is arranged concentrically within it and keyed upon a shaft D, having its bearings in the heads of the casing and in pedestals E. The shaft D is shown, Fig. 1, provided with a wheel D'. The piston C has two radial wings c, which are arranged diametrically opposite and work in frictional contact with the casing A. Packing c' (see Fig. 2) is arranged in the outer edges of the wings c, the same being formed of thin metal strips of right-angular form, which overlap at their inner ends.

As shown in Fig. 2, there are three abutments G G' G², that slide in slots and ways a, formed in the periphery of the casing A and within the steam-chests H. The latter have steam inlet and outlet ports h h' on opposite sides of the abutments. The latter are forced outward by double eccentrics I, fixed on the shaft D exterior to the ends of the casing A. The required connection between the abut-

ments G and eccentric I is established by means of arms J, (see Figs. 1, 3, and 4,) which are rigidly attached to the abutments G G' G² 55 exteriorly and project radially inward over the ends of the casing A. The inner ends of said arm J are provided with antifriction-rollers, that work in contact with the eccentric I. The three abutments G G' G² are located equidistantly, thus practically dividing the annular steam-chamber formed between the casing A and the piston C into three equal segmental spaces or compartments. The piston C having but two wings 65 c, which are diametrically opposite, it is apparent that steam will always be working expansively and under high pressure in one segmental compartment or chamber, so that uniform rotary speed of the engine is attained and a dead-center avoided. As shown in Fig. 3, the arms J of the abutment G have just passed one of the cams or projections i of the eccentric I, and, as shown in Fig. 2, the said abutment has just passed a wing 75 c of piston C', and the adjacent valve K being open steam is being admitted between the said wing and abutment and is acting against both, with the result that the piston C is rotated accordingly. The other valves K' K² 80 are closed and steam is working expansively in the next segmental chamber in order of rotation while exhausting freely from the same chambers on the other side of the piston-wings c. It will be understood that the abutments G G' G² are normally held drawn inward, as in Fig. 2, by springs J'. (See Fig. 1.) When forced outward to their farthest limit by the eccentrics I, acting on their arms J, their inner edges will be flush with the inner surface of the casing A, thus allowing the piston-wings c to pass.

As shown in Fig. 2, the inner ends of the abutments are provided with round grooves to hold packing g.

A cylinder L is arranged tangentially on the ends of the casing A, adjacent to each steam-chest H, and its piston rod l is pivoted to an arm k, fixed on the short rock-shaft k', whose inner arm k' carries a valve K or K' K². 100 It will be seen that by oscillating the outer arm k a valve K will be moved and the steam-port h opened or closed. The inner ends of the rock-arm k are beveled or scarfed and

adapted to engage the similarly-beveled outer ends of a slideable trip-bar M, of which there are two, arranged opposite and alined and also held slideably in keepers or guides m on the 5 eccentrics I.

A spiral spring N is coiled about each trip-bar M and acts against a keeper m and a collar O, which is clamped on the bar and adapted for adjustment thereon to vary the length 10 and tension of the spring N.

Each cylinder L is provided at the end adjacent to the rock-arm k with a tube or check-valve l', (see Figs. 3 and 4,) which admits air slowly to that side of the piston. An air-cushion may be provided on the other side 15 of said piston. It is hence apparent the cylinder L and its piston practically constitute a dash-pot whose action serves to effect and regulate the closure of the valves K.

It will now be understood that as the eccentric I revolves with the shaft D and piston C the trips M strike and press upon the rock-arms k and force the latter back, so that the valves are opened and held momentarily open for admission of steam through 20 ports h, and that as the piston and cam rotate further a trip M disengages from an arm k and allows the connected and adjacent valve to be quickly closed by the tension of the 25 vacuum in the cylinder.

A spring may be substituted for the dash-pot with the same general effect, but not with the same advantage.

A governor is formed by connecting the 30 weighted lever-arms P, Figs. 1 and 4, to the inner ends of the trip-rods M by means of links p, the said arms being fulcrumed on a yoke Q, fixed on the shaft D adjacent to the eccentric, and thus rotating with them. Now 35 when the engine starts the weighted governor-arms P are in such position as to hold the trips M so as to act on and open the valves, and thereby allow full admission of steam. When the load on the engine decreases, the latter will speed up, and the 40 governor-balls will in consequence be thrown outward by centrifugal action, thus drawing the valve-trips M inward or toward the shaft D, so that they will have less lap on the rock-arms K, and hence the two parts M k will not 45 remain in contact so long a time and the valves K K' K² will necessarily close more quickly. In case the rotative speed becomes excessive the governor proper will draw the 50 trips M so far inward as to be entirely out of range of contact with the valve-arms k, and thus shut off steam until speed is reduced.

The cut-off is regulated by adjusting the 55 collars o lengthwise of the trip-rods M, since this determines the length of the lap of the two trip members on the valve-arms k. Thus the cut-off may be regulated so as to secure the effect of the full expansion of steam, since the initial pressure is on one of the piston-wings e while the other is approaching the 60 last part of its stroke.

It will be understood that the exhaust-ports h' are always open.

What I claim is—

1. In a rotary engine, the combination with 70 a rotary shaft, a cylindrical casing and abutments sliding radially in peripheral slots in said casing and provided with radial arms extending inward, of the concentric piston fixed on the shaft and having radial wings, eccentrics on the shaft exterior to the casing, which 75 coact with the abutment-arms, valves for controlling admission of steam, means arranged on the casing and tending to hold the valves normally closed, a device connected with the 80 valves, trips which coact with said device to cause it to yield and open the valves more or less, trip mechanism rotating with the cams, and governor mechanism regulating engagement of the trips with the valve-operating 85 devices, substantially as shown and described.

2. In a rotary engine, the combination with 90 a rotary shaft, a cylindrical casing and abutments sliding radially in peripheral slots in said casing and provided with radial arms extending inward, of the concentric piston fixed on the shaft and having radial wings, eccentrics on the shaft exterior to the casing, which 95 coact with the abutment-arms, valves for controlling admission of steam, means arranged on the casing and tending to hold the valves normally closed, a movable arm connected with the valve, a trip-rod which is held slidably and radially and acts on the valve-arms at each rotation, and governor-levers for acting 100 on the said trip-rods, as shown and described.

3. In a rotary engine, the combination with 105 a rotary shaft, a cylindrical casing and abutments sliding radially in peripheral slots in said casing, and provided with radial arms extending inward, of the concentric piston fixed on the shaft and having radial wings, eccentrics on the shaft exterior to the casing, which 110 coact with the abutment-arms, valves for controlling admission of steam and each provided with an arm as specified, a dash-pot whose piston is connected with said arm, trip-rods held slidably and radially, and adapted to rotate with the eccentric, and to 115 lap with the valve-arms, weighted governor-levers connected with the trip-rods and tending to draw them inward by centrifugal action, substantially as shown and described.

4. In a rotary engine, the combination with 120 a rotary shaft, a cylindrical casing and abutments sliding radially in peripheral slots in said casing and provided with radial arms extending inward, of the concentric piston fixed on the shaft and having radial wings, 125 eccentrics on the shaft exterior to the casing, which coact with the abutment-arms, valves for controlling admission of steam, means arranged on the casing and tending to hold the valves normally closed, a rock-shaft and rock-arm connected with the valve, and said arm 130 having its free end beveled as described, a

dash-pot whose piston is connected with the valve-arm, a slideable trip-rod having its end beveled and adapted for contact and lap with such valve-arm, a spring coiled on said trip-
5 rod and having an adjustable device for regulating the tension of the spring, and weighted governor-arms pivoted on fixed points and rotating with the shaft and connected with the trip-rods for drawing the latter inward by
10 centrifugal action, substantially as shown and described.

5. In a rotary engine, the combination with a cylindrical casing, of a concentric piston having two radial wings, three slideable abut-
15 ments arranged radially and equidistantly in the casing, a valve-chest having induction and exhaust ports on opposite sides of each abutment, sliding valves adapted to close the induction-ports, a rock-shaft and rock-arms
20 for moving each valve, one of said arms being exterior to the chest, slideable trip-rods held in guides and arranged radially to the shaft and in the same vertical planes with

the outer valve-arms for contact therewith at each rotation of the piston, weighted gov- 25 ernor-arms loosely connected with the trip-rods and fulcrumed on a yoke to work in the same plane with the shaft, all arranged and operating as shown and described.

6. In a rotary engine, the combination with 30 the casing, sliding abutments, rotary eccen- trics, and the piston having wings, of a gov- ernor, slideable trip-rods operated by the latter, swinging valves controlling induction-ports and having arms arranged exteriorly for con- 35 tact with the trip-rods, the dash-pots fixed on the casing and having pistons connected with the valve-arms and provided with contracted air-openings on the side adjacent to the valve-arms, to operate as specified, for quickly 40 closing the valves.
